CLAIM

The ornamental design for a watch case, as shown and described.

DESCRIPTION

FIG. 1 is a perspective view of the invention;

FIG. 2 is a top view of the invention;

FIG. 3 is a bottom view of the invention;

FIG. 4 is a front view of the invention;

FIG. 5 is a back view of the invention, with the watch case inverted;

FIG. 6 is a side view of the invention, showing the side that contains a centrally-positioned mechanism used to control the watch; and,

FIG. 7 is another side view of the invention, showing the side opposite that shown in FIG. 6.

The views in the drawings are shown on different scales.
